L.L.P.(57) **CLAIM**

The ornamental design for a garment, as shown and described.

DESCRIPTION

FIG. 1 is a front left perspective view of a garment showing my new design;

FIG. 2 is a front elevational view thereof;

FIG. 3 is a rear elevational view thereof;

FIG. 4 is a left side elevational view thereof; and,

FIG. 5 is a right side elevational view thereof.

The evenly spaced broken lines depict portions of the garment that form no part of the claim. The dot-dash broken lines are boundary lines, which define the bounds of the claimed design. None of the broken lines form part of the claimed design.
